UNITED STATES PATENT OFFICE

HARRY B. BARRETT, OF LOS ANGELES, CALIFORNIA, ASSIGNOR TO H. B. BARRETT CO., LIMITED, OF LOS ANGELES, CALIFORNIA, A CORPORATION OF NEVADA

BRAKE-DRUM-TRUING MACHINE

Application filed January 22, 1929. Serial No. 334,315.

My invention relates to and has for a purpose the provision of a simple and durable machine by which one or more cuts can be taken from the periphery of a brake drum 5 of a vehicle wheel, in a manner to render the periphery of the drum perfectly true and concentric with the axis of the wheel on which the drum is mounted, as is highly desirable and in fact a necessity in order to obtain 10 maximum braking efficiency from the drum when in use.

It is a further purpose of my invention to provide a compact and portable brake drum truing machine of comparatively light 15 weight, which, with a brake drum carrying wheel removed from the vehicle and resting substantially horizontally on a support, is capable of being applied to and supported as a unit by the wheel during the truing operation, and in such manner as to insure the 20 utmost accuracy in truing the drum so that the necessity for a large and permanently installed expensive machine will be dispensed with, and yet the truing operation performed 25 with accuracy and but a minimum expenditure of time and labor.

It is a still further purpose of my invention to provide a brake drum truing machine embodying means for signaling the completion 30 of the truing operation and for automatically discontinuing the supply of power to the machine when the truing operation has been completed so as to prevent a needless consumption of power and wear of the 35 moving parts of the machine.

It is another purpose of my invention to provide a brake drum truing machine embodying a simple and positively acting mechanism by which the operation of a tool feeding carriage can be controlled to either cause 40 a power feed of the carriage or permit a manual feed as desired, with a means embodied in a feeding means for the carriage by which the feeding of the carriage will be automatically discontinued in the event that the supply 45 of power to the machine be continued after a cut upon the drum has been completed, so that damage to the machine as a result of continued feeding of the carriage will be 50 positively prevented.

I will describe only one form of brake drum truing machine embodying my invention and will then point out the novel features thereof in claims.

In the accompanying drawings, 55 Fig. 1 is a view showing in front elevation, one form of brake drum truing machine embodying my invention.

Fig. 2 is a view in side elevation of the machine shown in the preceding figure. 60

Fig. 3 is an enlarged vertical sectional view taken on the line 3—3 of Fig. 1 and looking in the direction of the arrows. 65

Fig. 4 is a horizontal sectional view taken on the line 4—4 of Fig. 1 and looking in the 65 direction of the arrows.

Referring specifically to the drawings in which similar reference characters designate similar parts in each of the several views, my invention in its present embodiment comprises an arbor A adapted to be detachably secured to a conventional form of vehicle wheel W carrying a brake drum D, in such manner that with the wheel removed from the vehicle and resting in a horizontal position on suitable supports such as a pair of beams B, the arbor will be supported by the wheel in axial alignment with the wheel axis and will extend vertically upward from the brake drum side of the wheel. In the present 80 instance the arbor is in the form of a shaft of uniform diameter and is provided at its lower end with a tapered threaded socket 10 which threadedly receives a threaded shank 11 formed on a mandrel 12 extending through the hub of the wheel and provided with oppositely disposed conical sleeves 13 and 14 which co-operate with a nut 15 threaded on the lower end of the mandrel, and one or more washers 16 interposed between the nut and 90 wheel hub, to center and secure the mandrel in the hub. With the shank 11 of the mandrel tightly screwed into the socket 10 of the arbor, it will be clear that that arbor will be rigidly supported by the wheel in axial 95 alignment with the wheel axis.

A carriage C is slidably mounted on the arbor A by means of a key 17 which provides a splined connection between the arbor and carriage operating to prevent rotation of the 100

latter on the arbor yet rendering the carriage free to travel along the arbor. A tool holder H is rotatably mounted on the arbor below the carriage C and is operatively connected to the carriage for sliding movement with the latter on the arbor so that in response to rotation of the holder, and with a suitable tool 18 carried by the holder, in engagement with either the inner or outer periphery of the 5 brake drum, a cut will be taken from the drum concentric with and parallel to the axis of the wheel, thus rendering the peripheral surface of the drum perfectly true, to insure a maximum braking effect from the drum when 10 in use.

15 To operatively connect the holder H to the carriage C for sliding movement along the arbor by the carriage while rendering the holder free to be rotated on the arbor, the 20 holder is provided with an axial hub 19 (Fig. 2) having an annular outwardly projecting flange 20 freely entering an axial socket 21 formed in the lower end of the carriage C. Also mounted in the socket 21 on opposite 25 sides of the flange 20 are thrust bearings 22 and 23; and to retain the bearings and flange against displacement from the socket, a plurality of studs 24 having lock nuts 25, are threaded radially into the lower end of the 30 carriage and project into the socket immediately below the lower thrust bearing 23. The inner ends of the studs 24 are of conical form as indicated at 25^a and engage the underside of the thrust bearing 23, so that in the event 35 of any wear occurring on the bearings, the resulting clearance can be removed by screwing the studs inwardly of the socket, the inner conical ends 25^a forming wedges to force the bearing 23 upward in the socket.

40 The holder H is thus suspended from the carriage C for sliding movement on the arbor by the carriage; and assuming that the tool 18 is taking a cut from the drum D during upward movement of the carriage on the 45 arbor, the tool will be pulled upwardly by the carriage and as a result prevent chattering of the tool on the drum.

45 In the present instance the tool 18 is detachably secured to a bar 26 by a set screw 27, and the bar projects at a right angle from a supporting member 28 slidably mounted in the head 29 of the tool holder at right angles to the length of the arbor and to one side of the latter as clearly shown in Fig. 4. 50 A key 30 restricts the member 28 to sliding movement in the head; and to provide for adjustment of the tool 18 to accommodate brake drums of different sizes and depths of cuts as well as to lock the tool in a selected 55 position of adjustment, an adjusting screw 31 having a crank handle 32 is journaled in a U shaped frame 33 secured to the head 29, and is threaded axially into the member 28 so that by rotating the screw the member and 60 hence the tool will be fed inwardly or out-

wardly of the head and will be automatically locked in a selected position of adjustment.

To provide means for rotating the tool holder H, I preferably provide an electric motor M which is supported by a bracket 34 secured to the upper end of the carriage C. To the shaft 35 of the motor is fixed a set of pulleys 36 of respectively different diameters, over any one of which is adapted to be trained an endless belt 37 also adapted to be trained over any one of a set of pulleys 38 reversely disposed from the pulleys 36 and fixed to a drive shaft 39 journaled in spaced apart brackets 40 secured to the carriage C by studs 41. To the drive shaft 39 between the brackets 40 is fixed a worm 42 which constantly meshes with a worm wheel 43 fixed to the hub 19 of the tool holder H so that with the motor M in operation the holder will be rotated on the arbor, and by shifting the position of the belt 37 on the sets of pulleys 36 and 38 the speed of rotation of the holder and hence the tool 18 can be varied.

As the holder is rotated, the carriage C is adapted to be simultaneously fed upwardly on the arbor A, so as to feed the tool 18 upwardly across the periphery of the drum D; and to this end a second worm wheel 44, constantly meshing with the worm 42 at the opposite side of the latter, is fixed to a shaft 45 journaled vertically in an arm 46, pivoted between the brackets 40 on a pin 47, and having fixed thereto at its upper end, a second worm 48 meshing with a third worm wheel 49 fixed to a stub shaft 50 journaled in a pair of spaced apart brackets 51 secured to the carriage C. Also fixed to the stub shaft 50 is a bevel gear 52 constantly meshing with a similar bevel gear 53 fixed to a feed screw 54 journaled vertically at its lower end in a socket 55 formed in one of the brackets 51, and held against upward endwise displacement from the socket by means of an abutment 56 secured to the carriage and abutting the hub of the bevel gear 53 above the latter.

The feed screw 54 threadedly engages a nut 57 in the form of an arm slidably on the arbor A and adapted to be fixed in a selected position of adjustment along the arbor by a set screw 58. It will thus be clear that when the motor M is in operation the feed screw 54 will be driven and will feed through the nut to cause the carriage C and hence the tool holder H to be fed upwardly along the arbor during rotation of the holder on the arbor.

The pivotal mounting of the shaft 45 on the pin 47 permits the shaft to be rocked laterally to either of two extreme positions, in one of which the worm 48 meshes with the worm wheel 49 to drive the latter as shown in Fig. 3 and in the other of which it is unmeshed with the worm wheel as is shown in Fig. 2 so as to permit the feed screw 54 to be reversely rotated manually by a crank handle 59 fixed to the feed screw, and thereby move

the carriage and tool holder downwardly on the arbor to their initial positions after the completion of a cut upon the drum.

The shaft 45 is normally urged outwardly from the worm wheel 49 to unmesh the worm 48 from the latter by means of a coil spring 60 interposed between and bearing against the arm 46 and an abutment 61 fixed to one of the brackets 40 as shown in Fig. 1. The shaft 45 is maintained in either of the positions shown in Figs. 2 and 3 against the normal tendency of the spring 60 to move the shaft away from the worm wheel 49, by means of a pin 61^a fixed to a lever 62 pivoted on a pin 63 and adapted to engage within either of two annular grooves 64 and 65 formed in the shaft 45, according as the lever 62 is rocked to the position shown in Fig. 2 or that shown in Fig. 3. The groove 64 being of greater depth than the groove 63 allows further outward movement of the shaft 45 than does the groove 63, and the difference in the depths of the two grooves is sufficient to allow unmeshing of the worm 48 and worm wheel 49, with a discontinuance of the power feed of the carriage.

It will be noted that the lower extremity of the feed screw 54 is provided with a reduced unthreaded portion 66 which is adapted to pass freely within the nut 57 so as to discontinue the upward feed of the carriage after a predetermined amount of travel of the carriage has been effected, so that possible damage to the machine is prevented. To further insure the machine against damage as well as to notify the operator that a cut upon the drum D has been completed, means is provided for operating an audible signal in the form of a bell 67 secured to the carriage C, as well as opening a switch 68 supplying current to the motor M and also secured to the carriage C.

This means in the present instance comprises a trip member T in the form of a rod having a vertical portion 69 vertically adjustable in the nut 57 and secured in a selected position of adjustment by a set screw 70; a horizontal portion 71 extending outwardly from the lower end of the vertical portion 69 and disposed in the path of an arm 72 for actuating the hammer 73 of the bell 67; and a second vertical portion 74 depending from the horizontal portion 71 and disposed in the path of the operating arm 75 of the switch 68.

The operation of the machine is as follows:

Assuming that the machine is supported on the wheel W as shown in the drawings, and with the worm 48 unmeshed from the worm wheel 49, the tool 18 is adjusted vertically on the arbor by manipulating the handle 59 until the tool is positioned at the lower edge of the drum D. The tool is then adjusted horizontally by manipulating the handle 32 to effect the desired depth of cut upon the drum by the tool.

The trip member T is adjusted vertically

so that after a sufficient upward travel of the carriage C to complete the cut, the bell 67 will be sounded and the supply of current to the motor M discontinued. The lever 62 is then manipulated to mesh the worm 48 with the worm wheel 49 after which the switch 68 is closed. With the motor in operation, the tool holder H will be rotated and the carriage C fed upwardly on the arbor to accordingly draw the holder upwardly and thereby cause the tool to travel across the periphery of the drum, thus cutting a predetermined thickness of material from the drum and rendering the latter perfectly concentric with and parallel to the axis of the wheel axis.

Should the operator not be present when the cut is completed and should the bell fail to sound or be heard, or the trip member T fail to open the switch 68, and thus permit the motor to continue to operate, the reduced unthreaded portion 66 of the feed screw 54, upon entering the nut 57 will automatically discontinue the upward feed of the carriage so that damage to the machine will be positively prevented.

From the foregoing description it will be manifest that broadly speaking I have provided a compact and portable machine capable of being supported by a brake drum carrying wheel when removed from the vehicle, and embodying an arbor, a carriage, and a tool carrying holder functionally related and co-operating in such manner as to insure that a cut taken upon the periphery of the drum will be absolutely concentric with and parallel to the wheel axis, all without the necessity of providing a heavy and expensive permanently installed machine, while affording all the desirable qualities of accuracy in the results obtained, economy, and a minimum expenditure of time and labor in setting up the machine on the work and the performance of the truing operation.

Furthermore it will be noted from a consideration of Figures 1 and 2, that all the elements supported from the arbor A are so positioned with respect to each other as to maintain the arbor in its upright position and hence the wheel W in its horizontal position, due to the fact that the weights of the various elements are substantially counterbalanced about the arbor and therefore reduce to a minimum the possibility of tilting the arbor from its upright position.

Although I have herein shown and described only one form of brake-drum truing machine embodying my invention, it is to be understood that various changes and modifications may be made therein without departing from the spirit of the invention and the spirit and scope of the appended claims.

I claim:

1. A brake drum truing machine comprising an arbor, means for fixedly securing the arbor to a brake drum carrying wheel in ax-

ial alinement with the wheel axis, a carriage 5
slidably mounted on the arbor and fixed 10
against rotation thereon, a tool carrying 15
holder rotatably mounted on the arbor and 20
operatively connected to the carriage for 25
sliding movement on the arbor by the 30
carriage so that with the tool of the holder 35
engaging the periphery of the brake drum, a 40
cut will be taken from the drum concentric 45
with and parallel to the wheel axis, means 50
for feeding the carriage along the shaft, and 55
means for rotating the holder.

2. A brake drum truing machine comprising 15
an arbor, means for fixedly securing the 20
arbor to a brake drum carrying wheel in axial 25
alinement with the wheel axis, a carriage 30
slidably mounted on the arbor and fixed 35
against rotation thereon, a tool carrying 40
holder rotatably mounted on the arbor and 45
operatively connected to the carriage for 50
sliding movement on the arbor by the 55
carriage so that with the tool of the holder 60
engaging the periphery of the brake drum, a 65
cut will be taken from the drum concentric 70
with and parallel to the wheel axis, means 75
for feeding the carriage along the shaft, and 80
means for rotating the holder.

3. A brake drum truing machine comprising 15
an arbor, means for fixedly securing the 20
arbor to a brake drum carrying wheel in axial 25
alinement with the wheel axis, a carriage 30
slidably mounted on the arbor and fixed 35
against rotation thereon, a tool carrying 40
holder rotatably mounted on the arbor and 45
operatively connected to the carriage for 50
sliding movement on the arbor by the 55
carriage so that with the tool of the holder 60
engaging the periphery of the brake drum, a 65
cut will be taken from the drum concentric 70
with and parallel to the wheel axis, means 75
for feeding the carriage along the shaft, and 80
means for rotating the holder, said feeding 85
means for the carriage comprising a nut 90
fixed to the arbor, a feed screw threadedly 95
engaging the nut and connected to the 100
carriage to move the latter along the arbor in
one direction or the other according as the
feed screw is rotated in one direction or the
other, and means for rotating the feed screw.

4. A brake drum truing machine comprising 15
an arbor, means for fixedly securing the 20
arbor to a brake drum carrying wheel in axial 25
alinement with the wheel axis so that with 30
the wheel disposed horizontally on a support, 35
the arbor will extend vertically upward from 40
the brake drum side of the wheel and will be 45
supported by the latter; a carriage slidably 50
mounted on the arbor and fixed against 55
rotation thereon; a tool carrying holder rotatably 60
mounted on the arbor below the carriage; 65
means for operatively connecting the holder 70
to the carriage for sliding movement of the 75
holder along the arbor by the carriage, yet 80
rendering the holder free to rotate on the 85
arbor so that with the tool of the holder 90
engaging the periphery of the brake drum a 95
cut will be taken from the drum concentric 100
with and parallel to the axis of the wheel; 105
means for feeding the carriage along the 110
arbor.

5. A brake drum truing machine comprising 15
an arbor; means for fixedly securing the 20
arbor to a brake drum carrying wheel in axial 25
alinement with the wheel axis so that with 30
the wheel disposed horizontally on a support, 35
the arbor will extend vertically upward from 40
the brake drum side of the wheel and will be 45
supported by the latter; a carriage slidably 50
mounted on the arbor and fixed against 55
rotation thereon; a tool carrying holder rotatably 60
mounted on the arbor below the carriage; 65
means for operatively connecting the holder 70
to the carriage for sliding movement of the 75
holder along the arbor by the carriage, yet 80
rendering the holder free to rotate on the 85
arbor so that with the tool of the holder 90
engaging the periphery of the brake drum a 95
cut will be taken from the drum concentric 100
with and parallel to the axis of the wheel; 105
means for feeding the carriage along the 110
arbor; and means for rotating the holder.

6. A brake drum truing machine comprising 15
an arbor; means for fixedly securing the 20
arbor to a brake drum carrying wheel in axial 25
alinement with the wheel axis so that with 30
the wheel disposed horizontally on a support, 35
the arbor will extend vertically upward from 40
the brake drum side of the wheel and will be 45
supported by the latter; a carriage slidably 50
mounted on the arbor and fixed against 55
rotation thereon; a tool carrying holder rotatably 60
mounted on the arbor below the carriage; 65
means for operatively connecting the holder 70
to the carriage for sliding movement of the 75
holder along the arbor by the carriage, yet 80
rendering the holder free to rotate on the 85
arbor so that with the tool of the holder 90
engaging the periphery of the brake drum a 95
cut will be taken from the drum concentric 100
with and parallel to the axis of the wheel; 105
means for feeding the carriage along the 110
arbor; and means for rotating the holder.

7. A brake drum truing machine comprising 15
an arbor; means for fixedly securing the 20
arbor to a brake drum carrying wheel in axial 25
alinement with the wheel axis so that with 30
the wheel disposed horizontally on a support, 35
the arbor will extend vertically upward from 40
the brake drum side of the wheel and will be 45
supported by the latter; a carriage slidably 50
mounted on the arbor and fixed against 55
rotation thereon; a tool carrying holder rotatably 60
mounted on the arbor below the carriage; 65
means for operatively connecting the holder 70
to the carriage for sliding movement of the 75
holder along the arbor by the carriage, yet 80
rendering the holder free to rotate on the 85
arbor so that with the tool of the holder 90
engaging the periphery of the brake drum a 95
cut will be taken from the drum concentric 100
with and parallel to the axis of the wheel; 105
means for feeding the carriage along the 110
arbor; and means for rotating the holder.

- arbor; and means for rotating the holder, said means for operatively connecting the holder to the carriage comprising an axial socket in the carriage, a hub on the holder having an outwardly projecting annular flange disposed in the socket, thrust bearings above and below the flange, and a plurality of retaining elements extending into the socket and engaging the lower thrust bearing to maintain the holder suspended from the carriage. 5
7. A brake drum truing machine comprising an arbor; means for fixedly securing the arbor to a brake drum carrying wheel in axial alinement with the wheel axis so that with the wheel disposed horizontally on a support, the arbor will extend vertically upward from the brake drum side of the wheel and will be supported by the latter; a carriage slidably mounted on the arbor and fixed against rotation thereon; a tool carrying holder rotatably mounted on the arbor below the carriage; means for operatively connecting the holder to the carriage for sliding movement of the holder along the arbor by the carriage, yet rendering the holder free to rotate on the arbor so that with the tool of the holder engaging the periphery of the brake drum a cut will be taken 10 from the drum concentric with and parallel to the axis of the wheel; means for feeding the carriage along the arbor; and means for rotating the holder, the holder being suspended from the carriage so as to be drawn upwardly on the arbor by the carriage in effecting cutting of the drum by the tool and thereby prevent chattering of the tool. 15
8. A brake drum truing machine comprising an arbor, means for fixedly securing the arbor to a brake drum carrying wheel in axial alinement with the wheel axis, a carriage slidably mounted on the arbor and fixed against rotation thereon, a tool carrying holder rotatably mounted on the arbor and operatively connected to the carriage for sliding movement on the arbor by the carriage so that with the tool of the holder engaging the periphery of the brake drum, a cut will be taken from the drum concentric with and parallel to the wheel axis, means for feeding the carriage along the shaft, and means for discontinuing feeding of the carriage when the cut has been completed. 20
9. A brake drum truing machine comprising an arbor; means for fixedly securing the arbor to a brake drum carrying wheel in axial alinement with the wheel axis so that with the wheel disposed horizontally on a support, the arbor will extend vertically upward from the brake drum side of the wheel and will be supported by the latter; a carriage slidably mounted on the arbor and fixed against rotation thereon; a tool carrying holder rotatably mounted on the arbor below the carriage; means for operatively connecting the holder to the carriage for sliding movement of the holder along the arbor by the carriage, yet rendering the holder free to rotate on the arbor so that with the tool of the holder engaging the periphery of the brake drum a cut will be taken from the drum concentric with and parallel to the axis of the wheel; a worm wheel fixed to the holder, a drive shaft journaled in the carriage, a worm fixed to the shaft and constantly meshing with the worm wheel to effect rotation of the latter and hence the holder, and means for driving the shaft comprising an electric motor supported on the carriage, and a driving connection between the motor and drive shaft. 25
10. A brake drum truing machine comprising an arbor; means for fixedly securing the arbor to a brake drum carrying wheel in axial alinement with the wheel axis so that with the wheel disposed horizontally on a support, the arbor will extend vertically upward from the brake drum side of the wheel and will be supported by the latter; a carriage slidably mounted on the arbor and fixed against rotation thereon; a tool carrying holder rotatably mounted on the arbor below the carriage; means for operatively connecting the holder to the carriage for sliding movement of the holder along the arbor by the carriage, yet rendering the holder free to rotate on the arbor so that with the tool of the holder engaging the periphery of the brake drum a cut will be taken from the drum concentric with and parallel to the axis of the wheel; a worm wheel fixed to the holder, a drive shaft journaled in the carriage, a worm fixed to the shaft and constantly meshing with the worm wheel to effect rotation of the latter and hence the holder, and means for driving the shaft comprising an electric motor supported on the carriage, and a driving connection between the motor and drive shaft. 30
11. A brake drum truing machine comprising an arbor; means for fixedly securing the arbor to a brake drum carrying wheel in axial alinement with the wheel axis so that with the wheel disposed horizontally on a support, the arbor will extend vertically upward from the brake drum side of the wheel and will be supported by the latter; a carriage slidably mounted on the arbor and fixed against rotation thereon; a tool carrying holder rotatably mounted on the arbor below the carriage; means for operatively connecting the holder to the carriage for sliding movement of the holder along the arbor by the carriage, yet rendering the holder free to rotate on the arbor so that with the tool of the holder engaging the periphery of the brake drum a cut will be taken from the drum concentric with and parallel to the axis of the wheel; a worm wheel fixed to the holder, a drive shaft journaled in the carriage, a worm fixed to the shaft and constantly meshing with the worm wheel to effect rotation of the latter and hence the holder, a second shaft journaled in the carriage, a worm wheel fixed to the second 35

shaft and meshing with said worm, a nut fixed to the arbor, a feed screw threadedly engaging the nut and connected to the carriage to move the latter along the arbor in response to 5 rotation of the feed screw, means for operatively connecting the second shaft and feed screw for rotation of the latter from the second shaft, and an electric motor supported by the carriage for driving the first mentioned 10 shaft.

12. A brake drum truing machine comprising an arbor; means for fixedly securing the arbor to a brake drum carrying wheel in axial alignment with the wheel axis so that with 15 the wheel disposed horizontally on a support, the arbor will extend vertically upward from the brake drum side of the wheel and will be supported by the latter; a carriage slidably mounted on the arbor and fixed against rotation thereon; a tool carrying holder rotatably mounted on the arbor below the carriage; means for operatively connecting the holder to the carriage for sliding movement of the holder along the arbor by the carriage, 20 yet rendering the holder free to rotate on the arbor so that with the tool of the holder engaging the periphery of the brake drum a cut will be taken from the drum concentric with and parallel to the axis of the wheel; a 25 worm wheel fixed to the holder, a drive shaft journaled in the carriage, a worm fixed to the shaft and constantly meshing with the worm wheel to effect rotation of the latter and hence the holder, a second shaft journaled in the carriage, a worm wheel fixed to 30 the second shaft and meshing with said worm, a worm fixed to the second shaft, a third shaft journaled in the carriage, a worm wheel fixed to the third shaft and meshing 35 with the second mentioned worm, a nut fixed to the arbor, a feed screw threadedly engaging the nut and connected to the carriage to move the latter along the arbor in response to 40 rotation of the feed screw, a pair of meshing bevel gears fixed to the feed screw and third shaft, and an electric motor supported on the carriage for driving the first mentioned shaft.

13. In a brake drum truing machine having a carriage and means for feeding the carriage, a disconnectible power feed device comprising a shaft, gears for operatively connecting the shaft with the feeding means to drive the latter in response to rotation of the 55 shaft, means for mounting the shaft for rotation and for rocking movement laterally to occupy one position wherein the gears will mesh and another position wherein the gears will be unmeshed, means for normally urging the shaft to the position wherein the gears will be meshed, and means for retaining the shaft in either of its positions against the action of said urging means.

14. In a brake drum truing machine having a carriage and means for feeding the

carriage, a disconnectible power feed device comprising a shaft, gears for operatively connecting the shaft with the feeding means to drive the latter in response to rotation of the shaft, means for mounting the shaft for rotation and for rocking movement laterally to occupy one position wherein the gears will mesh and another position wherein the gears will be unmeshed, means for normally urging the shaft to the position wherein the gears will be meshed, and means for retaining the shaft in either of its positions against the action of said urging means, comprising a pair of annular grooves of different depths formed in the shaft, and a pivoted lever having a pin engaging within one or the other of said grooves according as the lever is moved to one position or another.

15. A brake drum truing machine comprising an arbor, means for fixedly securing the arbor to a brake drum carrying wheel in axial alignment with the wheel axis so that with the wheel resting horizontally on a support, the arbor will extend vertically upward from the brake drum side of the wheel and will be supported in its upright position by the wheel, a tool carrying holder rotatably and slidably mounted on the arbor, and means supported from the arbor for driving the holder to effect rotation and sliding movements thereof on the arbor so that with the tool of the holder engaging the periphery of the brake drum a cut will be taken from the periphery, the elements supported from the arbor being so positioned with respect to each other as to maintain the arbor in its upright position and hence the wheel in its horizontal position.

16. A brake drum truing machine comprising an arbor, means for fixedly securing the arbor to a brake drum carrying wheel in axial alignment with the wheel axis so that with the wheel resting horizontally on a support, the arbor will extend vertically upward from the brake drum side of the wheel and will be supported in its upright position by the wheel, a tool carrying holder rotatably and slidably mounted on the arbor, and means supported from the arbor for driving the holder to effect rotation and sliding movements thereof on the arbor so that with the tool of the holder engaging the periphery of the brake drum a cut will be taken from the periphery, the elements supported from the arbor being so positioned with respect to each other that their weights will substantially counterbalance each other about the arbor to reduce to a minimum the possibility of tilting the arbor from its upright position and hence tilting the wheel from its horizontal position.

HARRY B. BARRETT.
